(57) **CLAIM**

The ornamental design for a potty liner, as shown and described.

DESCRIPTION

FIG. 1 is a top plan view of the potty liner showing my new design, with the broken lines being illustrative of environmental structure only and forming no part of the claimed design;

FIG. 2 is a front elevational view of the potty liner of FIG. 1;

FIG. 3 is a bottom view of the potty liner of FIG. 1;

FIG. 4 is a side elevational view of the potty liner of FIG. 2 viewed from the left thereof;

FIG. 5 is a side elevational view of the potty liner of FIG. 2 viewed from the right side thereof;

FIG. 6 is a rear elevational view of the potty liner of FIG. 2;

FIG. 7 is a top plan view of a second embodiment of potty liner without shield in accordance with the invention, with the broken lines being illustrative of environmental structure only and forming no part of the claimed design, the bottom view being substantially identical to the bottom view of FIG. 3; and,

FIG. 8 is a front elevational view of the potty liner of FIG. 7, the elevational views being substantially identical.
